METHOD AND MEANS FOR THE MANUFACTURE OF CUT FILLING PILE FABRICS

Owen D. Frost, Waynesboro, Va., assignor to Crompton-Shenandoah Co. Inc., a corporation of Virginia

Application May 28, 1948, Serial No. 29,802

28 Claims. (Cl. 139—116.5)

1

The present invention relates to a novel method and means for the manufacture of cut filling pile fabrics, such as corduroys, velveteens and other fabrics wherein the pile consists of filler threads intermeshed with warp threads of the ground fabric.

In accordance with the conventional method of manufacture of such fabrics, a pile filling is alternatively interlaced with and floated over a suitable number of ground warp threads. The woven fabric is removed from the loom and, after stiffening, brought to a cutting stand, where a cutter guide is manually inserted and retained in each of the warpwise races formed under the floats, thus making possible the cutting of the floats and hence the formation of the pile. This cutting operation not only requires a high degree of skill on the part of the operator as well as in tooling the guide and knife, but is, at least in the case of velveteens and the finer grades of corduroy, extremely time consuming, due to the fact that only a limited number of races can be cut at the same time. Although the time factor is objectionable even in the case of corduroys, it is obviously much more objectionable in the case of velveteens, the races of which must be cut one at a time.

Due to the high degree of skill required for cutting both corduroys and velveteens, the slowness thereof and the inefficiency occasioned by separate consecutive weaving, stiffening and cutting operations, numerous efforts have been made to arrange the cutters directly on the loom in such position that the floats are cut soon after being formed. Thus, it has been suggested to weave a special warp guide wire into each warpwise race of floated pile fillings, this wire lying below the floats of pile filling but not interlacing with the ground filling or warp, and serving to guide the race to a cutter arranged on the front of the loom, which is designed to cut the floats so as to give a cut pile fabric. These special warp guide wires are drawn into the loom from a special beam located in the vicinity of the warp beam, and wound, after being liberated from the fabric by the cutting of the floats, onto a special roll or beam. These so-called warp wire pile looms had many concomitant disadvantages. For example, efficient pile cutting was practically impossible because of the inherent vibration of the loom and the difficulty of maintaining constant and equal the tension of the individual wires; the drawing-in of a large number of wires from a beam is most impractical; convenient supervision of the loom operation is prevented

5 due to the location of the cutters; the lengths of wires required and the consequent investment therein are both excessive, coupled with the necessity of cutting the wires if the full wire length is not to be woven. As a result of these many drawbacks, the warp-wire pile looms have not been generally introduced into the pile fabric industry, the manufacturing of cut pile filling fabrics being today still effected, for the most 10 part, by the uneconomical and difficult method of cutting the floats in a separate operation after the fabric has been removed from the loom.

I have now discovered a new method and means for the manufacture of cut filling pile fabrics which, while effecting the weaving and cutting simultaneously, and providing for automatic guiding of the races to the cutters, has substantially none of the disadvantages inherent in the warp-wire looms heretofore suggested. In the 15 filling pile-cutting loom of my invention I provide a plurality of continuous wire loops, every two of which are woven, over a section of their perimeter, into a separate warpwise-race of floated pile fillings, and which guide said race to 20 cutter knives, where the floated fillings are cut, the cut pile fabric moving onto a cloth roll, while the continuous wire loops return to the loom to be again woven in pairs under new floated fillings which are in turn guided infallibly to the 25 cutters. A special compensator assures constant tension of the wires while they are being shedded, means also being provided for maintaining the wires taut during the cutting, as well as for taking up any slack that may be present in said 30 loops.

35 Further characteristics and advantages of my invention will appear from the following detailed description, read in conjunction with the drawing, in which:

40 Fig. 1 is a diagrammatic view of a pile cutting loom in accordance with my invention;

45 Figs. 2 and 3 are side elevations showing one embodiment of certain parts of the loop wire pile loom of my invention, Fig. 3 being the continuation of Fig. 2;

50 Fig. 4 is a diagrammatic showing of one scheme for drawing the wires through the compensator shown in Fig. 2;

Fig. 5 is a diagrammatic showing of an alternative scheme for drawing the wires through the compensator shown in Fig. 2;

Fig. 6 is a fragmentary view of one part of the compensator of my invention shown along plane 55 6—6 of Fig. 2;

Fig. 7 is a right side view of the showing of Fig. 6;

Fig. 8 is a top plan view of the showing of Fig. 6;

Fig. 9 shows a detail of construction;

Fig. 10 is an end view of the showing of Fig. 9;

Fig. 11 is a diagrammatic showing of the pile cutting operation in accordance with my invention.

Referring to Fig. 1, which diagrammatically illustrates the loop wire pile loom of my invention, 1 designates a yarn warp beam, from which the warp ends 2 pass up and over whip roll 3. The warp ends then pass through the warp stop motion drop wires 4, and after threading through lease rods 5 pass through ordinary warp harnesses 6a, 6b, 6c, 6d, 6e, 6f, these warp ends being hereinafter designated 2a, 2b, 2c, 2d, 2e, 2f respectively (compare Fig. 11). While, for purposes of illustration, six such harnesses are shown in the drawing, it is evident that these may be multiplied, in the manner known in the textile art, according to the pattern being woven. From harnesses 6, the shedded warp ends 2 pass through reed 8 carried by lay 38 which beats up the filling thread 9 inserted by shuttle 10 into the fell of cloth 11, which then passes over take-up roll 13, cloth 11 being held against the greater part of the periphery of said roll 13 by guide roll 14 over which cloth 11 passes on its further path.

In addition to the conventional warp ends 2, there are provided special continuous wire loops 20, consisting for instance of lengths of wire of high-tensile strength, the ends of which have been butt-welded together to form continuous loops. These loops pass from guide bar 21 through stop motion device 4 and through the heddle eyes of special harnesses 7a, 7b, 7c, 7d, the number as well as the pegging of which may be varied according to the intricacy of the pile pattern being woven. The shedding is always such however that a pair of continuous wire loops 20a and 20d, 20b and 20c respectively (Fig. 11) are laid in each race formed over warps 2a, 2b and 2c, 2d, 2e and 2f respectively by pile filler threads 9b, 9d and 9g, 9c, 9f and 9h respectively, fillers 9a and 9e being the ground filling. While in the diagrammatic showing of Fig. 1, each of the wire loops 20 is drawn through a separate heddle 7, it is evident that alternatively each pair of wire loops may be drawn through a separate heddle. In this case necessary precautions are taken to assure that the wire loops of each pair lie in the same horizontal plane within said heddle eye. While such drawing-in drafts can be used to advantage when weaving ordinary fabrics, the use of a separate heddle for each wire is preferable for the weaving of fabrics with wire warps under high tension.

After being drawn through harnesses 7, the wire loops 20 are threaded through reed 8. The two wires for any particular race may be threaded through the same dent of the reed; thus wires 20d and 20a may pass through one dent and wires 20b and 20c through another dent. Preferably, however, the wires for a particular race pass through separate dents, in which case a particular dent will carry one wire from each of two contiguous races; thus wires 20a and 20b will pass through one dent, and wires 20c and 20d through the next dent. The latter arrangement was used in the weaving of the fabric shown in Fig. 11, and is generally preferable so as to prevent crossing of the wires in the race before reaching the point of cutting. It is obvious that regardless of the

reeding employed, the two wires for any given race always lie on different sides of the corresponding cutter 85 (see Fig. 11).

The filler thread 9 (Fig. 1) having now been inserted in the shed by shuttle 10, and having been beaten up into the fell of cloth 11, the wire loops 20 are carried forward with the advance of the cloth by their intermeshing with filling 9 (compare Fig. 11), and pass with cloth 11 over take-up roll 13, surfaced for instance with card clothing, downwards via guide roll 14 and then horizontally via guide rolls 15 and 16 under false floor 17, on which the operator may stand to better supervise the perfect functioning of both the loom part and the cutting part of the loop wire cut pile loom of my invention. From guide roll 16, fabric 11 passes upwards over drag roll 19, being held against the latter by guide roll 18, and thence onto cutting table 78. The rear edge of this table is true and fabric 11 preferably passes upwards to it from drag roll 19 at a small angle, for example 5°, so as to assure the laying flat of fabric 11 on table 78. Circular cutters 85 mounted over this table effect the cutting of the floats of pile fillers 9b, 9c, 9d, 9f, 9g, 9h (Fig. 11) thus liberating wire warps 20a, b, c and d. The cut pile fabric 22 now passes downwards over the front, true edge of table 78, and, at an angle of preferably about 40°, over a second drag roll 23, being held against the latter by guide roll 24, over which it passes on its way to cloth roll 25. Rolls 19, 23 and 25 may be suitably driven through friction clutches (not shown in the drawing), thus making possible an adjustment of the tension of the fabric. Fabric 22, as removed from cloth roll 25, is a high quality filling pile fabric in the grey, requiring no further cutting operation or the stiffening ordinarily preceding such cutting. As no stiffening is required, the conventional neutralizing of the stiffening caustic prior to scouring is also eliminated, the abolishment of this step being a further characteristic advantage of the method of manufacturing cut pile fabrics in accordance with my invention.

As wire loops 20 are released from fabric 11 by the cutting operation, they are carried forward, at an angle of about 1° above the horizontal, over guide-bar 26, into the nip of a pair of feed rolls 27 and 28 (Fig. 1), preferably surfaced with a yielding material such as, for instance, rubber. The above-mentioned 1° angle, it is to be noted, is determined by the position of rolls 26 and 29. Rolls 27 and 28 are positively rotated (by drive means not shown in the drawing) in the direction indicated by the arrows, their peripheral velocity being slightly in excess of the speed of advance of cloth 22. Rolls 27 and 28 are preferably resiliently mounted and vertically adjustable with respect to each other. The function of rolls 27 and 28 is to impart a slight tension to wire loops 20, so as to maintain said wires taut at the point of cutting, this tension also serving to relieve to some extent the tension on yarn warp ends 2, thus reducing the number of yarn warp breaks. It is obvious that various other tensioning means may be employed for this purpose, such as for instance individual springs slidably connected at one end to wire loops 20, the other ends being adjustably fixed to a suitable support, so as to permit of adjustment of the spring tensions. Numerous other embodiments of this tensioning means will immediately be apparent to the skilled artisan, but I prefer to employ the above described rolls 27, 28, due to their simplicity as well as to their improved performance.

After emerging from this tensioning means, wire loops 20 pass under guide-rod 29 to guide-rod 30, and thence around pulleys 31, each wire loop 20 passing around a separate pulley 31 (Figs. 1 and 3), these pulleys serving for the taking up of slack in the wire loops 20, primarily that slack resulting from the wire loop forming operation hereinafter described. Pulleys 31 are individually attached, for instance by wires 80, to rods 81 supported in frame 82. Frame 82 is suspended from supporting framework 68 in a horizontally adjustable manner, so as to permit forward or backward movement thereof for adjustment of the tension on wire loops 20 occasioned by pulleys 31.

Upon leaving pulleys 31, wire loops 20 (Figs. 2 and 3) pass upwards under guide-rod 32, over guide-rod 33 and then, commencing their return course, horizontally to compensator, being possibly supported on this horizontal course by further guide-rods, such as 34 and 35.

Compensator 40 (Figs. 1, 2, 4-8) consists of a number of upright heddles 41, through the eyes of which wire loops 20 are threaded. Each of the heddles 41 is attached at its lower end to a spring 43, which takes up slack in wire loops 20 caused by the shedding of wire harnesses 7 (Fig. 1), thus making a tight shed and preventing loose wire loops from breaking warp ends 2. Preferably the number of such heddles 41 is equal to the total number of heddles in harnesses 7, although there may be, if desired, a lesser number of heddles 41 where each of wire loops 20 pass through a separate heddle of harnesses 7, each pair of wire loops 20a, 20d being threaded, for instance, through one of heddles 41, and each pair of wire loops 20b, 20c being threaded through another heddle 41. Alternatively, where the wire loops 20a, 20d and 20b, 20c respectively are threaded pairwise in harnesses 7, there may be a greater number of heddles 41 than of heddles in harnesses 7, this arrangement being preferable even in this case.

Heddles 41 are arranged in sections transverse to the direction of advance of wire loops 20, two of such sections 45 and 46 being shown for purposes of illustration in Fig. 1, while two additional sections 46 and 47 are shown in Fig. 2, there being thus, in the specific embodiment shown by way of example in the drawing, one section of heddles 41 for each loop wire harness 7, in accordance with the preferred embodiment of my invention. These sections are held together in spaced parallel relationship to each other by a supporting structure consisting of longitudinal members 48 and 49 and uprights 50 and 51 (Fig. 2). Each of sections 44, 45, 46, 47 in turn comprises a framework consisting of transverse members 52, 53, 54 and lateral uprights 55 (Figs. 6 and 8). The heddles within each section, for example section 44, shown in Fig. 6, are staggered in two rows, thus making it possible to accommodate a greater number of heddles in each section. The heddles slide in aligned openings 56 and 57 (see Fig. 7) in transverse members 52 and 53 respectively, the heddles being of non-circular cross-section and openings 56 and 57 being of corresponding cross-section, so as to prevent turning of the heddles. Tension springs 43 are connected to the end of each heddle 41, the lower end of said springs 43 being alternatively connected to two cross rods 58 and 59. Rods 58 and 59 are secured in position by a number of eye screws 60 and 61 respectively, which in turn are adjustably mounted on bottom transverse mem-

ber 54 so that the tension of springs 43 can be readily varied to an equal extent.

Between each heddle section 44, 45, 46, 47, as well as between section 44 and upright 50 and section 47 and upright 51, there are mounted in longitudinal members 48, cross-bars 65, 64, 63, 66, 62 respectively, extending parallel to said sections. Wire loops 20a, 20b, 20c, 20d entering compensator 40 over cross-bar 35 first pass (as shown in Fig. 2 and diagrammatically in Fig. 4) over cross-rod 62, whereupon wire loop 20a passes through eye 42a of heddle 41a and then over cross-rods 63, 64, 65 and 66; wire loop 20b passes over cross-rods 62 and 63, then through eye 42b of heddle 41b and over cross-rods 64, 65 and 66; wire loop 20c passes over cross-rods 62, 63 and 64 through eye 42c of heddle 41c and over cross-bars 65 and 66; loop 20d passes over cross-rods 62, 63, 64, 65, then through eye 42d of heddle 41d and then over cross-rod 66. Alternatively the drawing-in scheme of Fig. 5 may be used.

After passing out of compensator 40, the wire loops 20 (Fig. 1) pass over guide-bar 67 downwards to guide-bar 21, located just behind whip roll 3, with its underside slightly, for example 1", above the top of said whip roll. The direction of travel of wire loops 20 is again changed approximately 90° by guide-bar 21 and the wire loops 20 are pulled horizontally into the loom, repeating the operations described in the foregoing. It is evident that by this arrangement the wire loops in no way interfere with the twisting in of new warp ends 2.

Referring now to Figs. 2 and 5, compensator 40, guide-bars 30, 32, 33, 34, 35 and 67 as well as, already mentioned frame 82, are mounted on a supporting framework 68, which framework is in turn supported at a suitable height over the pile cutting loom of my invention (as can be noted from the diagrammatic showing of Fig. 1). The means of support may be any means known per se, it being for instance possible for framework 68 to rest on uprights (not shown in the drawing) extending from the floor of the pile-cutting loom. It is also possible however for said framework 68 to rest on rails (not shown in the drawing) which are suspended from the ceiling. When it is desired to change the fabric construction or design being woven, framework 68, together with compensator 40, frame 82, and guide-bars 30, 32, 33, 34, 35 and 67 can be removed from the support and replaced by a duplicate previously loaded with wires 20, thus avoiding the necessity of holding my cut pile loom idle while new wires 20 are being drawn into compensator 40 and around the said guide-bars. It is to be emphasized however that unless a radically different cut pile pattern repeat is to be woven, there is absolutely no necessity whatsoever of inserting new wires, wire loops 20 of constant given length continuing indefinitely on their limited endless path. The consequently, strictly limited amount of wire required is one important characteristic of the cut pile loom of my invention.

Guide-bars 21, 26, 29, 30, 32, 33, 34, 35 and 67 (Figs. 1, 2 and 3) may consist of stationary round shafting into which there is set suitable spacer means, for example an open-end comb 127 (see especially Figs. 9 and 10), the teeth 128 of which are so spaced as to accommodate the number of wire loops 20 required for the type of fabric to be woven. A cap 129 is preferably provided for each comb. Each dent of combs 127 accommodates only a single wire loop 20, thus preventing the formation of any false twist. While

guide-bars 21, 26 and 29 are preferably stationary so as to decrease the possibility of any lateral shifting of wires, the rest of the guide-bars may alternatively be developed rotatably, for instance positively rotated in the direction of advance of wire loops 20, at a peripheral velocity equal to or not substantially in excess of the speed of advance of the woven fabric. In this case the spacer means may suitably comprise spaced circular discs mounted on said bars. Of course, within the generic concept of my invention, the spacer means may be of any suitable construction so long as they perform the function of separating the wires and thus prevent false twist in wire loops 20. I prefer the use, however, of stationary guide-bars, the spacer means of which comprise loosely mounted circular discs.

While it may be observed (Fig. 1) that I employ circular cutters 85 for the cutting of the pile floats (9b, 9c, 9d, 9f, 9g, 9h, Fig. 11), it must of course be understood that other types of cutters may also be used, and for certain purposes, they may be replaced by reciprocating knives. Regardless of the type of cutter employed however, provision is made for adjustment of the vertical clearance with respect to cutting table 70, to assure optimum cutting performance regardless of the specific pile fabric being woven and cut.

As cloth 11 advances on cutter table 70 into cutting relationship to cutters 85 (Fig. 1), wire loops 20 are maintained taut by the pull exerted by the aforementioned tensioning means, for instance rolls 27, 28 so that upon liberation from the cloth, the wire loops pass forward at a small angle, as already mentioned, of for instance 1° above the horizontal. This angle may be increased up to, for example 45°, in which case the increased upward pull causes the floats (9b—d and 9f—h, Fig. 11) to be gradually stretched upward away from the ground of the fabric, thereby decreasing the possibility of cutters 85 injuring the ground. However, the resulting increased tension of these floats may make this undesirable, and I have diagrammatically shown in Fig. 11 the preferred case wherein the angle of lift of wire loops 20 is slight.

The wire loops being once threaded through the cut pile loom of my invention, they remain in their given positions without need of replacement or of further investment in new wire, as long as the pattern being woven is not changed. However, if it is desired to use the loom of my invention for the manufacture of a cut pile fabric requiring a different reed than the fabric for which the loom was originally set up, wire loops 20 must then be cut and new wire loops inserted according to the design of the new pile pattern to be produced. In this case the individual wires are threaded (Fig. 1) to the left of guide-bars 30 and 32, over guide-bars 33, 34 and 35, through compensator 40 and over guide-bar 67, all of which are mounted on frame 68 (Fig. 5). Wire loops 20, it is to be noted, are not as yet placed around pulleys 30. The forward ends of these wires are then brought a suitable distance over and beyond cross-bar 132 (Fig. 2) mounted on extension 133 hinged to frame 68. It is to be noted that cross-bar 132 is not provided with a comb. During the threading operation extension 133 is maintained parallel to frame 68 by means of hook 135 pivoted at 136 to extension 133, the free end of said hook engaging pin 137 of upright 138. Frame 68 is then brought above the cut pile loom of my invention and supported there in the manner described hereinabove. Hook 135 is then manually dis-

engaged from pin 137 so that support 133 drops downwards and wires 20 fall free from cross-bar 67. In this position the ends of wires 20 can be readily grasped by the loom operator and threaded around guide-bar 21 through stop motion 4, lease rods 5, harnesses 7 and reed 8 (Fig. 1). The loom part of my cut pile loom is now started in operation and weaving is continued until about 6 inches of wires 20 have been intermeshed in cloth 11. 10 Wire harnesses 7 are then raised and weaving is continued with harnesses 7 in this position for about 3 feet of fabric, the wires not being intermeshed with the fabric over this distance. Thereupon harnesses 7 are again set in operation according to the chain pattern, and weaving is continued until the second portion of cloth 11 interwoven with the wires has advanced to cutter table 70. The wires are then withdrawn from the rear (in the direction of advance of the cloth) from 20 the first 6 inches of interweaving. These wire ends are then passed from below, in pairs between the individual cutters 85 and over guide-bar 26, to between rolls 27, 28 and the free ends are then brought onto a welding table which is brought 25 directly behind guide-bar 29, and are butt-welded there to their other ends so as to form individual, continuous wire loops 20. After these continuous wire loops have been formed, the inevitably resulting slack thereof is taken up by placing these 30 wires over pulleys 81. Wires 80 (Fig. 3) of said pulleys are thereupon tautly connected to rods 81. When the slack has thus been removed from all of the wire loops 20, frame 82 may be shifted 35 horizontally for the purpose of adjusting the tension on wire loops 20.

Figure 11 shows diagrammatically one-and-a-half pattern repeats of a pile fabric made on the cut pile loom of my invention, both before and after cutting. It is of course understood that the cut pile loom of my invention is not restricted to the manufacture of this or any other specific pile pattern but may be utilized fully for the manufacture of the most varied cut pile filling fabrics including velveteens and corduroys, as well as their variations.

The foregoing specific description is for purposes of illustration and not of limitation and it is therefore my intention that the invention be limited only by the appended claims or their equivalents wherein I have endeavored to claim broadly all inherent novelty.

I claim:

1. In a loom including warp harnesses, shuttle and reed, adapted for the weaving of filling pile fabrics including warpwise races formed by the floating of pile filler threads over a plurality of warp threads, the improvement comprising at least one special sheddable harness, a plurality of continuous wire loops threaded through said special harness and said reed, and a plurality of cutters between which said wire loops pass on their continuous course.

2. In a loom including warp harnesses, shuttle and reed, adapted for the weaving of filling pile fabrics including warpwise races formed by the floating of pile filler threads over at least one warp thread, the improvement comprising at least one special sheddable harness, a plurality of continuous wire loops threaded through said special harness and said reed, said special harness being so threaded and so shedded as to insert a pair of wire loops warpwise in each of said races, and at least one cutter arranged between each of said pair of wire loops and in front, in the direction of advance of said fabric, of said reed.

3. The improvement according to claim 1 comprising, in addition, a compensator adapted to take up slack in said wire loops during the shedding of said special harness.

4. The improvement according to claim 3 wherein said compensator comprises spring-loaded members connected to said wire loops.

5. The improvement according to claim 4 wherein said spring-loaded members comprises heddles through the eyes of which said wire loops freely pass, and which heddles are free to reciprocate under spring action.

6. The improvement according to claim 5 wherein said heddles are secured against rotation.

7. The improvement according to claim 6 in which said heddles comprise non-circular heddle shafts which slide in correspondingly shaped guide surfaces.

8. The improvement according to claim 4 wherein each wire loop is connected to a separate spring-loaded member.

9. In a loom including warp harnesses, shuttle and reed, adapted for the weaving of filling pile fabrics including warpwise races formed by the floating of pile filler threads over a plurality of warp threads, the improvement comprising at least one special sheddable harness for each said race in the pattern repeat being woven, a plurality of continuous wire loops threaded through said special harness and said reed, and a plurality of cutters between which said wire loops pass on their continuous course.

10. In a loom including warp harnesses, shuttle and reed, adapted for the weaving of filling pile fabrics including warpwise races formed by the floating of pile filler threads over a plurality of warp threads, the improvement comprising a special sheddable harness, heddles in said special harness, a plurality of continuous wire loops, each of which is threaded through a separate one of said heddles and through said reed, and a plurality of cutters between which said wire loops pass on their continuous course.

11. In a loom including warp harnesses, shuttle and reed, adapted for the weaving of filling pile fabrics including warpwise races formed by the floating of pile filler threads over a plurality of warp threads, the improvement comprising a special sheddable harness, a plurality of continuous wire loops threaded through said special harness and through said reed, said special harness being so threaded and so shedded as to insert two wide loops warpwise in each of said races, each of said two wire loops passing through a different dent of said reed, and a plurality of cutters between which said wire loops pass on their continuous course.

12. In a loom including warp harnesses, shuttle and reed, adapted for the weaving of filling pile fabrics including warpwise races formed by the floating of pile filler threads over a plurality of warp threads, the improvement comprising at least one special sheddable harness, a plurality of continuous wire loops threaded through said special harness and said reed, a plurality of cutters between which said wire loops pass on their continuous course and means adapted to hold said wire loops taut as they advance past said cutters.

13. The improvement according to claim 12 wherein said means comprises a pair of cooperating rolls through the nip of which said wire loops pass.

14. The improvement according to claim 12 wherein said means are also adapted to deflect

said wire loops upwards as they advance past said cutters.

15. In a loom including warp harnesses, shuttle and reed, adapted for the weaving of filling pile fabrics including warpwise races formed by the floating of pile filler threads over a plurality of warp threads, the improvement comprising at least one special sheddable harness, a plurality of continuous wire loops threaded through said special harness and said reed, a plurality of cutters between which said wire loops pass on their continuous course, and means adapted to take up slack in said wire loops.

16. In a loom including warp harnesses, shuttle and reed, adapted for the weaving of filling pile fabrics including warpwise races formed by the floating of pile filler threads over a plurality of warp threads, the improvement comprising at least one special sheddable harness, a plurality of continuous wire loops threaded through said special harness and said reed, a plurality of cutters between which said wire loops pass on their continuous course, and adjustable means adapted to take up slack in said wire loops.

17. In a loom including warp harnesses, shuttle and reed, adapted for the weaving of filling pile fabrics including warpwise races formed by the floating of pile filler threads over a plurality of warp threads, the improvement comprising at least one special sheddable harness, a plurality of continuous wire loops threaded through said special harness and said reed, a cutter table over which said wire loops move while enmeshed in said fabric, and a plurality of cutters arranged over said table, in the longitudinal plane of said races, between which cutters said wire loops pass on their continuous course.

18. The improvement according to claim 17 comprising, in addition, means adapted to pull said fabric downwards upon leaving said table.

19. The improvement according to claim 18 comprising, in addition, means for adjusting the vertical distance of said blades from said cutter table.

20. In a loom including warp harnesses, shuttle and reed, adapted for the weaving of filling pile fabrics, including warpwise races formed by the floating of pile filler threads over a plurality of warp threads, the improvement comprising at least one special sheddable harness, a plurality of continuous wire loops threaded through said special harness and said reed, a plurality of cutters between which said wire loops pass on their continuous course, means adapted to hold said wire loops taut as they pass between said cutters, and a compensator adapted to take up the slack in said wire loops resulting from the shedding of said special harness.

21. In a loom including warp harnesses, shuttle and reed, adapted for the weaving of filling pile fabrics, including warpwise races formed by the floating of pile filler threads over a plurality of warp threads, the improvement comprising at least one special sheddable harness, a plurality of continuous wire loops threaded through said special harness and said reed, a plurality of cutters between which said wire loops pass on their continuous course, a compensator adapted to take up the slack in said wire loops resulting from the shedding of said special harness, and means adapted to take up the remaining slack in said wire loops.

22. In a loom including warp harnesses, shuttle and reed, adapted for the weaving of filling pile fabrics, including warpwise races formed by the

floating of pile filler threads over a plurality of warp threads, the improvement comprising at least one special sheddable harness, a plurality of continuous wire loops threaded through said special harness and said reed, a plurality of cutters between which said wire loops pass on their continuous course, a compensator adapted to take up the slack in said wire loops resulting from the shedding of said special harness, first means adapted to take up the remaining slack in said wire loops and second means adapted to hold said wire loops taut as they pass between said cutters.

23. The improvement according to claim 22 wherein said compensator and said first means are mounted on a replaceable support arranged above said special harness, said reed and said cutters.

24. The improvement according to claim 23 wherein said support is provided at its forward end in the direction of advance of said wire loops with a hinged extension.

25. In the manufacture of cut pile filling fabrics which includes intermeshing a pile filling with certain ground warp threads and floating it over other ground warp threads so as to form races of floated pile filling and thereupon severing said floated pile filler threads, the improvement comprising weaving continuous wire loops into said races, cutting said floats and thereupon continuously returning said wire loops for reweaving and recutting.

26. In the manufacture of cut pile filling fabrics which includes intermeshing a pile filling with certain ground warp threads and floating it over

35

other ground warp threads so as to form races of floated pile filling and thereupon severing said floated pile filler threads, the improvement comprising weaving at least two continuous wire loops into each of said races, cutting said floats and thereupon continuously returning said wire loops for reweaving and recutting.

27. In the manufacture of cut pile filling fabrics which includes intermeshing a pile filling with certain ground warp threads and floating it over other ground warp threads so as to form races of floated pile filling and thereupon severing said floated pile filler threads, the improvement comprising weaving at least two continuous wire loops into each of said races, guiding the said two continuous wire loops to embrace a cutter which severs said floats and thereupon continuously returning said wire loops for reweaving and reguiding to said cutters.

28. In the manufacture of cut pile filling fabrics which includes intermeshing a pile filling with certain ground warp threads and floating it over other ground warp threads so as to form races of floated pile filling and thereupon severing said floated pile filler threads, the improvement comprising shedding at least two continuous wire loops into each of said races, guiding the said two continuous wire loops to embrace a cutter which severs said floats, taking up the slack in said wires which ensues during shedding and thereupon continuously returning said wire loops for reweaving and reguiding to said cutters.

Certificate of Correction

Patent No. 2,490,041

December 6, 1949

OWEN D. FROST

It is hereby certified that errors appear in the printed specification of the above numbered patent requiring correction as follows:

Column 6, line 34, for "Figs. 2 and 5" read *Figs. 2 and 3*; column 9, line 53, for the word "wide" read *wire*; column 11, line 23, for "fililng" read *filling*;
and that the said Letters Patent should be read with these corrections therein that the same may conform to the record of the case in the Patent Office.

Signed and sealed this 28th day of March, A. D. 1950.
